WASHING MACHINE

Clarence D. Cathey and Jesse E. Miller,
Checotah, Okla.

Application November 1, 1944, Serial No. 561,424

1 Claim. (Cl. 68—183)

1

This invention relates to a washing machine and more particularly to an improved construction for washing soiled cloths or the like.

A primary object of this invention is the provision of an improved washing machine characterized by the absence of movable mechanical parts in the chamber in which the clothes are contained.

A further important object of this invention is the provision of improved means, comprising a passage of heated air through the water contained in such a device, for agitating the clothes, water and soap or washing powder, to effect the cleansing action of the clothes.

Still another object is the provision of such a washing machine whereby the wear and tear on clothing so washed is appreciably reduced.

Still another object is the provision of such a washing machine which is sturdy and durable in construction, reliable and efficient in operation, and relatively simple and inexpensive to manufacture and operate.

Still other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a side sectional view of one form of washing machine embodying the features of this invention.

Figure 2 is a sectional view taken substantially along the line 2—2 of Figure 1 as viewed in the direction indicated by the arrows, and

Figure 3 is a sectional view taken substantially along the line 3—3 of Figure 1 as viewed in the direction indicated by the arrows.

Like reference numerals refer to like parts throughout the several views of the drawings.

Having reference now to the drawings there is shown at 10 a supporting frame having a base plate 11, and adapted to support as in a peripheral groove 12 at its upper extremity, a receptacle 13 comprising the main body of the washer in which are adapted to be positioned clothes to be washed together with a quantity of water and appropriate washing material.

Secured to base plate in any desired manner, are a suitable source of power 14 which may comprise an electric motor, as in the illustrative embodiment, or any other desired type of motor driven by gasoline, oil, natural gas, or the like, and a blower 15 of any desired conventional type. From blower 15 an air duct 16 leads to a

2

conical receptacle 17 secured to the base of main receptacle 13 by any desired means, within which is positioned an electric or other suitable heating element 18, in the illustrative embodiment shown comprised of grid tubes 19 surrounded by electrical coils 20 and supplied with current from any desired source as through a wire 21 (see Figure 3). Grid 19 may be secured within the walls of receptacle 17 in any desired manner as by means of a series of bolts 22 engaging a circular rim 23 thereabout.

The base of receptacle 13 is provided with a centrally disposed threaded aperture, in which is secured in fluid tight relation, as by means of a spacing washer 24, an upwardly extending vertical tube 25. Surrounding tube 25 is a sleeve 26 of larger diameter than the tube 25 provided with a cover 27 at its upper extremity through which is passed a plunger rod 28 the interior extremity of which terminates in a cone valve 29, and the outer extremity of which terminates in a control knob 30.

The lower extremity of sleeve 26 terminates in an enlarged circular flange 31, supported as by risers or baffles 32 on a second circular flange 33 secured about the base of tube 25. A cover or lid 35 of any desired conventional type is provided for the receptacle 13, and has screened air vents 34 therein.

From the foregoing the operation of the device should now be readily understandable. Clothing, together with a predetermined quantity of water and soap are first placed in receptacle 13, and motor 14 energized to drive blower 15, which, in turn, passes air through duct 16 in the receptacle 17 where it circulates about the now energized heater 18. The heated air then passes upwardly through tube 25, the quantity passing therethrough being regulated by appropriate regulation of the valve 29, and thence downwardly through sleeve 26 and outwardly through the space provided between the plates 31 and 33 into the water in receptacle 13. The turbulent action of the air bubbles passing upwardly therethrough readily reacts on the soap particles to form a rich sud which then finds its way through the weave of the materials in the wash. The soil in the clothes is dissolved or loosened and separates and the movement of the clothes occasioned by the turbulence of the air readily permits the soil to settle out whereupon the heavy sediment settles at the bottom of the tub beneath the air baffles.

It will be readily understood that various attachments may be supplied to the instant inventive concept, as for example, a conventional

wringer to be driven by a motor 14 or thermostatic controls to control the temperature of the water within receptacle 18, as well as the temperature of the heating element 18.

Now from the foregoing it will be seen that there is herein provided an improved washer accomplishing all the objects of this invention and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

We claim:

In combination with a washing machine including a receptacle for clothes and water, a vented closure cover therefor, a source of power, an air blower operable thereby having a discharge air duct terminating in a conical receptacle underlying the major portion of the bottom of said receptacle and secured thereto, a heater for the air disposed in said conical receptacle positioned immediately below said receptacle bottom and underlying the major portion thereof, means for directing said heated air into said receptacle adjacent its base including a tube ex-

15 tending through the bottom of said receptacle terminating adjacent the top thereof, said tube being open at its upper end and communicating at its lower end with said conical receptacle, a sleeve closed at its upper extremity extending downwardly about and spaced from said tube and communicating at its lower end with a pair of outwardly extending spaced baffle plates, a plurality of radially extending vertical baffle plates disposed between said first mentioned baffle plates, and means for controlling the quantity of air admitted to said receptacle including a valve seat in the upper end of said tube and a valve therefor adjustable exteriorly of said sleeve.
